UNITED STATES PATENT OFFICE.

JAMES CRAIG, OF BUTLER, PENNSYLVANIA.

APPARATUS FOR POINTING BOLTS.

Application filed November 24, 1922. Serial No. 602,959.

To all whom it may concern:

Be it known that I, JAMES CRAIG, residing at Butler, in the county of Butler and State of Pennsylvania, a citizen of the United States, have invented or discovered certain new and useful Improvements in Apparatus for Pointing Bolts, of which improvements the following is a specification.

My invention relates to the machining of bolts and more particularly to the turning of pointed or rounded ends upon bolts. Bolts are formed from rolled stock from which ordinarily lengths of material are sheared, and it is requisite to form by a cutting operation a point upon the sheared-off length of stock or upon the blank otherwise prepared. The objects of my invention are simplicity of structure and adequacy and economy in operation. The invention is found not in apparatus merely but also in a method of effecting the desired cut.

This application is a continuation in part derived from my application filed June 6th, 1921, Serial No. 475,289, now Patent No. 1,440,376, June 2, 1923. In the parent application I have retained the method claims only, and in this application I shall describe and claim the apparatus.

In a third application filed March 18th, 1921, Serial No. 453,264, now Patent No. 1,440,375, Jan. 2, 1923, an application still pending in the Patent Office, I have described and claimed a bolt-pointing machine of the same general character as that to which my present invention is addressed. It is characteristic of that machine and of the machine of my present invention also that the bolt under treatment is rolled in a slot formed by and between opposite parallel cylindrical surfaces, the width of the slot being equal to the diameter of the bolt blank. One of these two surfaces is stationary, the other is movable, rotating on the common axis of the two cylindrical surfaces. It will be understood that, if a cylindrical article be so rolled between plane surfaces which extend parallel one to the other, the rate at which the rolled article will advance will be exactly half the rate of relative movement of the two surfaces; but it will further be understood that, when the rolling is between cylindrical surfaces, the rate of advance of the rolled article will not be exactly half the surface speed of the moving cylindrical surface. There is a new factor introduced, namely, the difference in radius of curvature

of the two surfaces, in consequence of which (in the machine of my prior application alluded to) the bolt, as a matter of fact, lags somewhat—that is to say, advances at something less than half the surface speed of the moving cylindrical surface (the surface of smaller radius). I have in the specification of that earlier application described the cutter for pointing the bolt as advancing at substantially half the speed at which the movable cylinder advances, and it will be understood from what has just been said that there must be a niceness of adjustment of relative speeds, to bring it about that the cutter shall advance in exact synchronism with the bolt blank.

In the machine of my present invention I eliminate the necessity of minutely adjusting the rate of advance of the cutter, to accord exactly with the rate of advance of the blank. I cause the cutter to advance at exactly half the speed of the moving cylinder and, adopting a cutter of the particular construction presently to be described, I take advantage of the difference in the rate of advance of cutter and of bolt blank, to effect the cutting operation.

In the accompanying drawings, Figure I is a view of the machine of my present invention seen in end elevation; Figure II is a similar view, drawn to larger scale, and affording a more minute illustration of a certain feature of the invention; Figure III is a view corresponding in scale with Figure I and showing the machine partly in side elevation, partly in medial and vertical section; Figure IV is a view in side elevation and to larger scale than Figure III, showing in detail certain elements of the machine; Figures V and VI are diagrammatic illustrations of the manner in which cutting is effected; Figure VII is a view in plan and in side elevation of a modification of, a refinement in the shape of the knife; and Figure VIII is a view in elevation of a bolt with a blunt point such as may be formed by employing such a knife as is particularly illustrated in Fig. VII.

On a shaft 1, suitably mounted and rotated from a suitable source of power, is integrally carried a drum 2. At an interval from and opposite the periphery of drum 2, a stationary block 3 is mounted. This block presents to drum 2 a concave cylindrical face, and its curvature is concentric with the cylindrical face of drum 2, the interval at

which drum 2 and block 3 stand apart (an interval equal to the diameter of the bolt to be pointed) may be nicely adjusted by securing block 3 to a standard 4 by bolts 5. The body of this standard (which as presently will appear serves other and additional purposes) is arranged opposite drum 2 at one side and at an interval from drum 2. It stands as shown in Figure III to rearward of drum 2, on the right. Shaft 1 extends through an opening in this standard. As shown in Figure I the peripheral extent of block 3 around drum 2 amounts to approximately 180°. The angular extent of this block is however not a matter of limitation; for, as will be apparent in the sequel, its extent may be greater or less, according to the particular shape and position of the knife and the consequent rapidity with which cutting is effected. If the extent be, as advantageously it is, approximately 180°, the block 3 will, in order to make possible the desired adjustment, be composed of sections.

The space between drum 2 and block 3 constitutes a slot *a*; in this instance it is semi-circumferential in its extent. When the machine is assembled it will be understood that a bolt introduced into this slot and lying in a line parallel with the axis of rotation (that is to say, longitudinally of the drum) will be simultaneously tangent to the opposite faces of drum and of block. It will further be understood that rotation of drum 2 within the stationary block 3 will cause a bolt so lying between, to roll. As the bolt rolls, it will advance along the slot in the direction in which the drum turns, and from what has gone before it will be understood that the rate of bolt advance relatively to block 3 will be slightly less than one-half the rate at which the surface of drum 2 turns relatively to block 3. Accordingly, each complete rotation of drum 2 will effect the advance of the bolt something less than half way around the drum; or, if the slot extends exactly half way round the drum, then it will require a little more than one complete rotation of the drum to cause a bolt blank to advance throughout the entire length of the slot.

What may be the value of this difference, what may be the actual value of the lag of the advancing bolt, is an ascertainable amount, calculable from the difference between the radii of curvature of the two opposing cylindrical surfaces.

Loosely mounted for free turning upon shaft 1, but secure against longitudinal movement upon the shaft, is the cutter wheel 12. It is arranged to rearward, that is to say on the right-hand side (Fig. III) of drum 2. The hub 7 of the cutter wheel is prolonged and extends freely through the opening in standard 4. This cutter wheel 12

is caused to rotate in the same direction with drum 2 and at half the speed of drum 2 by gearing interposed between shaft 1 and hub 7, this gearing being indicated at 8, 9, 10 and 11.

The cutter wheel 12 carries the cutter 13, its cutting edge *b*—*c* (as appears in Figure II) extends at once longitudinally of and also transversely of the slot *a*, and (as appears in Figure III) in the direction of the axis of the cylindrical surfaces which define the slot *a*. In other words, it is oblique both to the radius and to the axis of the cylindrical surfaces. Furthermore, as will appear in the uppermost presentation in Figure III, there is clearance in the formation of this knife 13 from its cutting edge rearward, that is to the right. The length of this knife measured in the line of its travel is equal approximately to the lag above described of the bolt blank in its advance through slot *a*, less the diameter of the bolt blank itself.

Adjacent the intake end of slot *a* (the right-hand end, Fig. I), a bar 14 is in stationary manner secured to constitute a shelf on which, as is best indicated in Fig. II, a blank *d* is made to lie with its body more than half enclosed in slot *a*. At this intake end the slot *a* is somewhat widened, as will preferably be effected by modifying slightly the curvature of the face of block 3, so that as the introduced blank *d* rests on the shelf 14, it will not be picked up and rolled along by the mere rotation of drum 2. Drum 2 is provided with one or more pairs of pivoted fingers 15, (cf. Figs. II and IV), whose free ends are held normally under spring tension to protrude slightly beyond the cylindrical surface of drum 2, and are so particularly shaped that, in the rotation of the drum, they come to position as is indicated in Figure II, and engage an introduced blank *d*, and crowd it against the slot-forming surface of block 3, and cause the blank to begin to roll. These fingers are so shaped and proportioned that they carry the blank rolling along slot *a* until the modification in the shape of the slot alluded to above has been passed, and until the blank comes into the normal portion of slot *a*, where it is simultaneously tangent both to block 3 and to drum 2. The pair of fingers 15, borne as they are by drum 2, move as a whole (that is to say, disregarding their pivotal movement) approximately twice as fast as blank *d* is rolled. Accordingly, the point of tangency of the fingers 15 upon the blank *d* advances along the tips of the fingers 15 until presently this point of tangency reaches the rear edge of the tip of the fingers, and thereafter the function of the fingers having been performed, the fingers are carried forward with the drum and in advance of the blank

until their services are again needed. Meanwhile the blank will have entered the normal portion of the slot *a*, and will be carried forward without the aid of fingers

- 5 15. Inasmuch as drum 2 travels at twice the speed of the cutters, there ordinarily will be half as many pairs of fingers 15 upon drum 2 as there are cutters upon wheel 12. The drawings show four cutters arranged at quadrant points upon wheel 12, and correspondingly two pairs of fingers 15 arranged diametrically opposite one another.
- 10 15. The cutter carrying wheel 12 is advantageously provided in the intervals between cutters and opposite the slot *a* with extended bosses 18 carefully proportioned, against which newly introduced blanks *d* may be brought to position ready for the cutting operation.

15 It will of course be understood that the shelf 14 will be so shaped that while sustaining a newly introduced blank *d*, it will not in any way interfere with the rotation 25 of the cutter-wheel 12 carrying at is does the cutters 13 and the arc-shaped bosses 18.

20 It remains to be remarked that there is no movement of the cutters in a direction perpendicular to the plane of their orbit; there 30 is no swinging of the cutters in their carrier; the cutter wheel and the parts which it carries advance as an integer. In this respect the machine of this application differs from the machine of my application

35 Serial No. 453,264, alluded to above. And it should in this connection be remembered that there is no longitudinal movement of the bolt under treatment, no feeding of it forward toward the cutter. Its motions are 40 rotation upon its axis and advance along slot *a*. The progressive cutting of the point is due to the fact that the cutting edge of the knife is inclined to the axis of the bolt from the forward end *b* to the rear end *c*; 45 that a portion only of the cutting edge engages the work at any given moment; and that this work-engaging portion progresses from end to end of the obliquely set edge.

50 Operation is as follows: The parts being assembled as shown in Figures I and III, the direction of rotation of drum 2 and of wheel 12 is anti-clockwise (cf. Fig. I) and the speed of rotation of drum 2 is as has already been made plain twice the speed of 55 rotation of wheel 12. An unpointed bolt is laid on the bar 14 and advanced until it abuts upon boss 18. Rotation of drum 2 presently brings a pair of fingers 15 into engagement with the blank *d*, the fingers 60 advancing confine the blank closely between themselves and the opposite face of block 3, and cause the blank to begin to roll and advance along the slot *a* in anti-clockwise direction. As the drum continues to turn, 65 the pair of fingers 15, yielding somewhat

under spring tension with which they are backed, still advance relatively to the blank, and presently pass ahead of the blank, but meanwhile they will have brought the blank beyond the widened part of slot *a*, and into 70 the portion of the slot which is of normal width. There the blank is engaged simultaneously by the normal opposite walls of the slot, and its rolling advance is continued without intermission. The blank advances 75 at something less than half the speed at which the surface of drum 2 advances, and at something less than the speed at which the cutter 13, immediately to rearward, advances.

80 Considering now the cutting operation more minutely, and beginning with the parts in the position shown at the right in Figures I and II, it will be seen that the cutting edge *b*—*c* of the knife is coming 85 into engagement with the end of the blank *d*. As operation progresses, the knife overtakes the blank; and, comparing the three positions shown somewhat diagrammatically in Figure I, arranged at quadrant points, it will be seen that in the course of the advance of the blank throughout the extent of its semi-circular path *a* the whole length of the knife passes across the diametrical width of the blank. On the right, 90 the knife is rearward of the blank. On the left, the blank is rearward of the knife, while at the intermediate point above, the knife wholly overlies the blank.

95 Turning now to Figure V of the drawings, the line *e*—*f* will indicate the position of the cutting edge of the knife relatively to the blank *d* at the moment when the blank enters the slot *a*. Presently the edge of the knife will overlie the blank on the line *g*—*h*, 100 and it will be observed that in this position a cut is being formed which extends from the center to the perimeter of the blank. As operation progresses, the edge of the knife will advance so that the line of cut 105 will come progressively to the positions indicated by the lines *i*—*j*, *k*—*l*, *m*—*n*, *o*—*p*. The line upon which the cut is progressing then advances with the operation from the center of turning toward the perimeter; 110 and meanwhile the clearance alluded to above in the shaping of the knife gives space for the developing point beyond the cutting edge of the knife. The outline of the ultimately formed point is in Figure 120 V indicated by the lines *t*—*r*—*s*.

115 Fig. VI is a diagrammatic showing, being a view of the blank in section, on the plane indicated by the line *k*—*l*, Fig. V, the operation of pointing having advanced until the 125 edge of the cutter lies in the line *k*—*l*, but no further. It will be observed that the point *r* has developed, and this point now lies within the under-cut at the edge of the knife. Cutting is progressing on so much 130

of the line $k-l$ as is indicated at $x-y$. This line of cut $x-y$ always extends to the periphery of the blank, and diminishes in length, until at the completion of the operation it is zero. The region $x-y$ of actual contact, of diminishing length, as already explained, is, as operation progresses, constantly advancing along the knife edge in the direction indicated by the arrow in Fig. VI.

10 It will immediately be apparent to the engineer that minute shaping of the knife edge makes possible minute gradation in the shape of the point which is cut. This point may be rounded,—a shape which 15 ordinarily is advantageous.

I have in Figure VII indicated such a modification in the shaping of the knife edge as will effect a modification in the shape of the point when cut, and in Figure 20 VIII I have indicated a bolt having a point of such shape as the knife of Fig. VII will produce. In this instance the edge of the knife $b-c$ is formed in two portions $b-z$ and $z-c$. The portion $b-z$ is so shaped as 25 to extend concentrically with respect to the center of turning of wheel 12 and the portion $z-c$ extends angularly with respect to the portion $b-z$. The effect of the portion $b-z$ of the edge, as will from what has 30 gone before be apparent, will be to cut a square end upon the blank; the effect of the portion $z-c$ inasmuch as it extends obliquely to the circumference in which the portion $b-z$ lies, will be generally the same 35 as the effect of the knife edge $b-c$ of Figs. II and IV, to cut a taper; the effect of the arching of the edge $z-c$, as shown in Fig. VII, will be to make a rounded taper; and, inasmuch as the portion $z-c$ of the cutting 40 edge begins to take effect after the blank has past part way beneath the knife, the effect of the whole edge will be to cut centrally a square end and peripherally a rounded taper, producing the shape particularly shown in Fig. VIII. Fig. VII 45 clearly indicates that the cutting edge $b-z-c$ is angled, and this angling is in two planes, and it will be apparent that by modification of these angles in one or the 50 other plane the shape of the finished end of the bolt may be varied at will.

I do not mean to limit myself to details of structure nor to details of machine operation. The reader will not fail to observe 55 that in some respects the machine is not identically the same as the machine of the companion method application, Serial No. 475,289, alluded to above, but in these respects my specifications are exemplary 60 merely. Furthermore, it is manifest that the invention is applicable not to the pointing of bolts merely, but generally to the shaping of the ends of spindle formed articles.

65 I claim as my invention:

1. In a machine for shaping the ends of spindle-formed articles, the combination of two cylindrical surfaces of concentric curvature spaced apart and movable in the direction of their parallelism, one relatively to the other, a cutter arranged opposite the slot formed by and between such surfaces, movable longitudinally of said slot, fixed in its position transversely of the slot, and having a cutting edge extending when the parts 70 are assembled longitudinally with respect to the slot and also longitudinally with respect to the axis of the said cylindrical surfaces, means for imparting to the said cylindrical surfaces relative rotation and means for imparting to said cutter rotation on common axis with the said cylindrical surfaces and at intermediate speed.

2. In a machine for shaping the ends of spindle-formed articles, the combination of 85 two cylindrical surfaces of concentric curvature spaced apart and movable in the direction of their parallelism, one relatively to the other, a cutter arranged opposite the slot formed by and between such surfaces, movable longitudinally of said slot, fixed in its position transversely of the slot, and having a cutting edge extending when the parts are 90 assembled in a line oblique to the radius of curvature, means for imparting to the said cylindrical surfaces relative rotation and means for imparting to said cutter rotation on common axis with the said cylindrical surfaces and at intermediate speed.

3. In a machine for shaping the ends of 100 spindle-formed articles, the combination of two cylindrical surfaces different in length of radius of curvature, coaxially arranged and rotatable one relatively to the other, and a cutter arranged opposite the slot formed 105 by and between such surfaces, movable longitudinally of said slot, fixed in its position transversely of the slot, the cutting edge of said cutter extending in a direction which is oblique at once to the radius of curvature 110 and to the axis of the cylindrical surfaces, means for imparting to the said cylindrical surfaces relative rotation and means for imparting to said cutter rotation on common axis with the said cylindrical surfaces and 115 at intermediate speed.

4. In a machine for shaping the ends of spindle-formed articles the combination of 120 two cylindrical surfaces different in length of radius of curvature, coaxially arranged and rotatable one relatively to the other, a cutter arranged opposite the slot formed by and between said surfaces and movable longitudinally of said slot at half the speed 125 of the relative movement aforesaid, fixed in its position transversely of the slot, the edge of said cutter extending obliquely to the radius of curvature, means for imparting to the said cylindrical surfaces relative rotation and means for imparting to said cut- 130

ter rotation on common axis with the said cylindrical surfaces and at intermediate speed.

5. In a machine for shaping the ends of spindle-formed articles, means for rotating a blank on its axis and for simultaneously impelling it in a direction perpendicular to its axis, a blade arranged opposite the path of blank advance, and means for moving 10 said blade along the path of blank advance and at a rate of speed different from that of an advancing blank, said blade having a cutting edge which extends longitudinally of the path of blank advance and obliquely 15 to the axis of an advancing blank.

6. In a machine for shaping spindle-formed articles, means for rotating a blank on its axis and for simultaneously impelling it in a direction perpendicular to its axis, 20 a blade extending opposite the path of blank advance and in a line oblique both to the axis of the blank and to the direction of its advance, and means for causing the blade to advance in the same direction with the 25 blank but at a different speed, said blade being fixed in its position longitudinally of the blank.

7. In a machine for shaping the ends of spindle-formed articles, a blank support and 30 a cutter, whose cutting edge extends in a

plurality of planes extending in different degrees of angularity with respect to the axis of a blank borne by said support, means for imparting to a supported blank a motion of rotation on its axis and a motion 35 of translation in a direction perpendicular to its axis relatively to said cutter.

8. In a machine for shaping spindle-formed articles, the combination of two cylindrical surfaces different in length of radius of curvature, coaxially arranged and rotatable one relatively to the other, the curvature of one of said surfaces being modified, whereby throughout a portion of its extent the slot formed by and between the 40 surfaces is widened, and a spring-backed pivoted finger whose relative movement is identical with the other of the two cylindrical surfaces, normally extending beyond such other surface and overlying the slot 45 formed by and between the said surfaces, and means for shaping the end of a blank as it is rolled by and in the slot between such surfaces and such cooperating finger.

In testimony whereof I have hereunto set my hand.

JAMES CRAIG.
